(57) CLAIM

The ornamental design for a lumbar heating and massage belt, as shown and described.

DESCRIPTION

FIG. 1 is a top, front, left side perspective view of a lumbar heating and massage belt, showing the claimed design; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; and, FIG. 8 is a bottom, rear, left side perspective view thereof. The dashed broken lines in the drawing depict portions of the lumbar heating and massage belt that form no part of the claimed design.

1 Claim, 7 Drawing Sheets
